UNITED STATES PATENT OFFICE

HERBERT R. STRATFORD, OF CLEVELAND, OHIO, ASSIGNOR TO THE STRATMORE COMPANY, OF CLEVELAND, OHIO, A CORPORATION OF OHIO

SURFACING APPARATUS

Application filed January 9, 1929. Serial No. 331,355.

The present invention, relating, as indicated, to surfacing apparatus, is more particularly directed to a new and improved semi-permanent element for use in surfacing or abrading such surfaces as wood and metal panels and panels coated with various materials. The principal object of the present invention is the provision of a composite unitary supporting pad and abrasive element for use in portable surfacing machines characterized by the application of the abrasive directly to the supporting pad and the ability to re-apply the abrasive as it may be worn or removed from the operating portion of the pad.

To the accomplishment of the foregoing and related ends, said invention, then, consists of the means hereinafter fully described and particularly pointed out in the claims; the annexed drawing and the following description setting forth in detail certain structure embodying the invention, such disclosed means constituting, however, but one of various mechanical forms in which the principle of the invention may be used.

In said annexed drawing:—

Fig. 1 is a partial central vertical section through my improved composite abrasive element and supporting pad; Fig. 2 is a plan view of the lower surface of the element of Fig. 1; Fig. 3 is a similar view showing a modification of the same; and Fig. 4 is a partial central section showing another modification of the element of Fig. 1.

The object of the present invention is the provision of a combined supporting pad and abrasive element to be used therewith in which abrasive may be recoated on the pad at those portions from which the abrasive is worn during use so that a single supporting structure may be employed indefinitely with repeated recoatings.

Referring now to Fig. 1, I have shown a supporting pad 1 intended to be secured to the extending shaft (not shown) of a portable surfacing machine. This pad 1, which may be formed of rubber, felt, reinforced rubber or similar material, must have some slight amount of flexibility and/or compressibility and is ordinarily supported by one or more

reinforcing plates 2 and 3. The amount of compressibility and flexibility of this supporting pad depends in each case upon the particular work for which it is intended and may be readily varied by the reinforcing means employed with the pad proper, as well as by the nature and thickness of the material forming the pad. In the pad shown the pad proper 1 may be formed of rubber in which are a series of spaced concentric grooves 5, 6 and 7. These encircling grooves serve the double purpose of providing a clearing space for the abrasive which is worn from the surface of the pad and the material which is worn from the surface of the article being operated upon and for providing increased flexibility in the pad. Where the pad is formed of felt or rubber, for example, these grooves may be incorporated in the pad during its manufacture, and during the application of the layer or coating of adhesive and abrasive a mask may be applied to the lower surface of the pad to cover the grooves therein so that adhesive will not enter these grooves and fill the same.

Adhesive is applied to the lower or operating surface of the pad and a layer of abrasive grains is then applied to the adhesive to produce an abrasive coating over the operating portion of the pad. As the pad is ordinarily employed against the work only the radially outer portion is engaged and the abrasive is removed from this portion first. After the removal of substantially all of the abrasive this portion of the pad may be re-coated with adhesive and abrasive and may be used over and over, providing a relatively inexpensive and satisfactory composite supporting pad and abrasive element.

In Fig. 3 I have shown radial grooves 10 as well as a circumferential groove 11, and various other arrangements of grooves may be employed in the surface of the pad to produce greater or less flexibility and more or less clearance space for the removed material and abrasive.

In Fig. 4 I have shown a modification of the pad just described, which consists of a molded supporting pad 15 formed of rubber or similar material and provided with a

series of recesses 16 having undercut portions 17. A composition consisting of adhesive and abrasive is filled into these openings and allowed to harden, thus providing a multiplicity of relatively solid abrasive plugs set into the compressible and/or flexible support 15. In this form of composite article the material which forms the support, namely the rubber or similar material, must be of a nature permitting it to wear off as the abrasive wears off and this may be accomplished by the introduction into the material of a certain amount of abrasive material.

The pad of Fig. 4 may, after a time, lose its plugs of combined abrasive and adhesive, and in this case these may be renewed of course by refilling the recesses with adhesive and abrasive and allowing the latter to set.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:—

1. A composite abrasive element consisting of a thin flexible backing disc, a compressible supporting pad mounted on said disc and provided on its exposed surface with a series of recesses and raised lands between said recesses, said pad having abrasive properties for an appreciable depth.

2. A composite abrasive element consisting of a compressible supporting pad provided with a narrow annular weakened area concentric with the axis of the element and spaced from the periphery of the element to increase the flexibility of the element along the line of the weakened area, said pad having abrasive properties for an appreciable depth.

3. A composite abrasive element consisting of a compressible supporting pad provided with a recess imparting weakness thereto along an approximately annular line concentric with the axis of the element to increase the flexibility of the element along such line, said pad having abrasive properties for an appreciable depth.

Signed by me, this 2nd day of January, 1929.

HERBERT R. STRATFORD.
